UNITED STATES PATENT OFFICE.

CHRISTOPHER F. HANKEY AND JOHN M. HANKEY, OF DANVILLE, ILLINOIS.

DESIGN FOR IRON FENCE.

Specification forming part of Design No. 6,274, dated November 26, 1872.

To all whom it may concern:

Be it known that we, CHRISTOPHER F. HANKEY and JOHN M. HANKEY, of Danville, in the county of Vermillion and State of Illinois, have invented a new and valuable Improvement in Designs for Iron Fences; and we do hereby declare that the following is a full, clear, and exact description of the construction and operation of the same, reference being had to the annexed drawing making a part of this specification, and to the letters and figures of reference marked thereon.

The figure is a representation of our invention, showing a front view.

My invention has relation to a design for wire picket-fences, and is fully illustrated in the accompanying drawing, in which—

The letters A A' represent the upper and lower horizontal bars of a fence-panel, and B B' the pickets, made of thick wire. The parts of said pickets between the bars A are vertical. Each picket is continued above the bar A, and is there bent over to a semicircular form, and its end brought in contact with the bar. The pickets are placed at equal distances apart. The end of the curved part b of each picket B falls in the center of the curved part

of the next adjoining picket B. The hooks or curved ends of the pickets B' are about one-half the diameter of those marked b, and are so arranged as to be concentric with the latter, as shown, the effect being very ornamental, and at the same time economical. These curved parts may be put on the fence independent of the pickets, and as an ornament, after the pickets have been arranged. E E designate the end posts of the panel. These may be of any design.

What we claim as our invention and desire to secure by Letters Patent, is—

The design of the concentric curved and interlaced tops of a wire fence—that is, each smaller semicircle embracing two spaces and three pickets, and each larger semicircle embracing four spaces and five pickets, substantially as specified.

In testimony that we claim the above we have hereunto subscribed our names in the presence of two witnesses.

CHRISTOPHER F. HANKEY.
JOHN M. HANKEY.
